UNITED STATES PATENT OFFICE.

ALVIN B. REDELL, OF CHICAGO, ILLINOIS.

INCANDESCENT GAS-LAMP.

SPECIFICATION forming part of Letters Patent No. 698,225, dated April 22, 1902.

Application filed July 1, 1901. Serial No. 66,703. (No model.)

To all whom it may concern:

Be it known that I, ALVIN B. REDELL, a citizen of the United States, residing at Chicago, in the county of Cook and State of Illinois, 5 have invented certain new and useful Improvements in Incandescent Gas-Lamps, of which the following is a specification.

One of the objects of this invention is the production of an incandescent gas-lamp embodying the improvements herein shown and described.

A further object is the production of means for supporting the mantle of a lamp of this character upon a delicate spring, whereby the 15 mantle will be saved from shocks and blows received by the lamp. As is well known, the mantle of an incandescent lamp is extremely fragile and easily broken—so delicate, in fact, that any considerable shock received by the 20 lamp-body shatters the mantle unless the latter is protected in some manner.

In the accompanying drawings, Figure 1 is a vertical central section through a lamp-burner embodying the features of my invention. Fig. 2 is a plan view of said burner. Fig. 3 is a vertical central section through the spring-holding tube on dotted line 3 3 of Fig. 5. Fig. 4 is a vertical section through said tube on dotted line 4 4 of Fig. 5. Fig. 5 is a 25 plan view of said spring-holding tube. Fig. 6 is a vertical central section through the mantle-supporting shell. Fig. 7 is a top plan view of said shell. Fig. 8 is a side elevation, partly in section, representing the cross-arm 30 in said mantle-supporting shell. Fig. 9 is a top view of said cross-arm. Fig. 10 is a vertical central section, and Fig. 11 an end view, of a tip adapted to rest upon the mantle-supporting spring and project into the conical 35 socket formed in said cross-arm. Fig. 12 is a side elevation, and Fig. 13 a top plan view, of a collar adapted to fit around the mantle-supporting shell to receive the mantle-supporting wire.

40 Like letters of reference indicate corresponding parts throughout the several views.

In the embodiment herein shown of this invention the mantle-supporting means is illustrated as an attachment adapted to be applied to any incandescent gas-lamp of common form. It, however, may be formed integral with the lamp-body.

A is the gallery of the burner, surrounding the central Bunsen tube A'. I provide a tube B, adapted to fit over the Bunsen tube A', 55 and in the upper end of this latter tube form two diametrically opposite slots B'. These slots are intended to receive the ears B² of the spring-supporting yoke B³, which ears are forced into the slots B'. The spring-supporting yoke extends downward within the tube B and at its lower end is folded over in the clip B⁴ to grasp the lower end of the flexible spring-holding wire B⁵, which rises vertically and axially through said tube B, 60 extending for some distance above the upper end of said tube. The tube B is provided with the diametrically opposite locking projections B⁶ for a purpose to be later mentioned herein. The yoke B³ is provided with 70 the shoulders B⁷, adapted to receive the conical coiled mantle-supporting spring C, which surrounds the spring-holding wire B⁵. The mantle-supporting shell D, tubular in form, is adapted to loosely telescope the tube B. 75 This shell is of a larger diameter at its upper portion than near its lower end and is provided with the cross-arm D', having the conical central pocket D², perforated at its upper end, and the securing-ears D³, adapted 80 to extend through perforations D⁴ in the sides of the shell D, and thus to hold said cross-arm in position within the upper enlarged portion of the shell D. The conical pocket D² is adapted to receive a cap D⁵, of 85 asbestos or other non-conducting material, axially perforated to receive the spring-holding wire B⁵ and to rest upon the top of the conical coil-spring C. Thus it will be seen that when the shell D is in position over the 90 tube B its weight will be borne by said conical spring. The mantle is supported by the shell D and is attached thereto in any convenient manner, as by the usual ring D⁶, having a rod D⁷ extending upward to suspend 95 the mantle from its upper end, said rod being secured relative to said ring by means of the thumb-screw D⁸. The ring D⁶ is held in position with relation to said shell by the notches D⁹ in the lower side of the ring, which 100 notches are adapted to engage the projections D¹⁰ in the shell. The location of the spring within the central tube removes it from the heat of the flame, and the non-con-

ducting cap further protects it from said heat. The lower annular edge of the shell D is curved inward and is adapted to embrace the locking projections B⁶ in order to hold 5 the mantle-supporting shell D in its lowest position against the action of its supporting-spring when it is desirable to relieve said shell of the spring-action, as in transporting or shipping the lamp. The shell D fits the 10 tube B rather loosely, and therefore permits not only a vertical reciprocation with relation to said tube, but also a sidewise yielding movement by reason of the flexibility of the spring-holding wire B⁵, in order to provide 15 against a shock from any direction and to thereby protect the delicate mantle from being broken. A perforated cap D¹¹, composed of wire-gauze or other material, is adapted to rest upon the upper side of the cross-arm D' 20 and the pocket D² thereof, and the usual wire-gauze screen D¹² is placed at the upper end of the shell D. The cap D¹¹ and the screen D¹² are intended to permit the passage of the 25 gas upward through the shell D and to prevent the flame from descending into said shell. The shell D being supported at a central point normally stands in an upright position. Should the weight of the mantle upon one side of the shell disturb its equilibrium, it may be readjusted by slightly 30 bending the cross-arm, thus moving the pocket D² relatively to the shell D.

As hereinbefore suggested, the spring-holding wire B⁵ acts not only as a guide to retain 35 the conical spring C in position, but by reason of its flexibility of itself constitutes a spring to cushion lateral shocks received by the lamp.

I have shown and described my invention 40 in the preferred form. However, I do not desire to limit myself to this construction alone, it being clear that it may be modified and changed to a considerable extent without departing from the spirit of my invention.

45. I claim as my invention—

1. In an incandescent lamp, in combination, a Bunsen tube; a mantle-supporting shell; and a spring in said shell, mounted above the upper end of the tube, for supporting the shell with relation to the tube.

50. 2. In an incandescent lamp, in combination, a Bunsen tube; a conical coil-spring mounted on its base above said tube; and a mantle-supporting shell surrounding said 55 conical spring, and resting upon the smaller end of said conical spring.

3. In an incandescent lamp, in combination, a Bunsen tube; a conical coil-spring mounted on its base above said tube; and a 60 mantle-supporting shell surrounding said conical spring, said shell having within its upper portion an arm resting upon the smaller

end of said conical spring, for supporting said shell.

4. In an incandescent lamp, in combination, 65 a lamp-gallery; a Bunsen tube; a mantle-supporting shell; and a spring extending from a point above the upper end of said Bunsen tube, which spring supports said mantle-supporting shell with relation to said tube. 70

5. In an incandescent lamp, in combination, 75 a lamp-gallery; a Bunsen tube; a spring-supporting tube telescoping with said Bunsen tube; a mantle-supporting shell; and a coil-spring seated in the upper end of said spring-supporting tube, for supporting the mantle-supporting shell.

6. In an incandescent lamp, in combination, 80 a lamp-gallery; a Bunsen tube; a spring-supporting tube telescoping with said Bunsen tube; a spring mounted in said spring-supporting tube; and a mantle-supporting shell having means for mounting said shell on said spring.

7. In an incandescent lamp, in combination, 85 a lamp-gallery; a Bunsen tube; a spring-supporting tube telescoping with said Bunsen tube; a conical coil-spring mounted in said spring-supporting tube; a mantle-supporting shell having means for supporting said shell 90 upon said spring; and means for attaching the mantle to said shell.

8. In a means for supporting incandescent mantles, in combination, a coil-spring; a 95 guide-rod; a mantle-supporting shell having means for supporting said shell upon said spring; and means for attaching the mantle to said shell.

9. In a means for supporting incandescent mantles, in combination, a coil-spring; a 100 guide-rod extending centrally through said spring; and a mantle-supporting shell having means for supporting said shell upon said spring and guiding it upon said guide-rod.

10. In a means for supporting incandescent mantles, in combination, a conical coil-spring; a guide-rod extending centrally of 105 said spring; and a mantle-supporting shell having an arm within the upper portion of said shell, for supporting said shell upon said spring and for guiding it upon said guide-rod.

11. In an incandescent lamp, in combination, a spring-supporting tube; a conical coil-spring supported by said tube; a guide-rod extending centrally of said spring; a mantle-supporting shell having an arm within the upper portion of said shell, for supporting said shell upon said spring and for guiding it upon said guide-rod; and means for attaching the mantle to said shell.

ALVIN B. REDELL.
